UNITED STATES PATENT OFFICE.

WILLIAM KENT KISE, OF KANSAS CITY, MISSOURI.

OIL STOVE.

Application filed October 30, 1926. Serial No. 145,334.

My invention relates to oil stoves and more particularly to burners for oil stoves.

It is a purpose of my invention to provide a new and improved oil vapor burner that is provided with means for preventing flooding of the same with oil, said means preferably comprising a drain opening in said burner located at a low point therein, the floor or bottom of the chamber in the burner preferably sloping continuously toward said drain opening.

It is a further object of my invention to provide means for igniting vapor passing from one of the groups of burner openings from the ignited vapor passing through another group of burner openings. The burner openings in stoves of this character are ordinarily arranged in groups, said groups being spaced along the burner and being ordinarily difficult to light one from the other, that is, the vapor or gas passing from one set of openings ordinarily will not ignite the vapor or gas passing from the other set of openings. As a result it is frequently necessary to ignite the vapor or gas passing from each set of openings separately. In a stove in which the vapor that is used for fuel is generated by means of a flame from the burner, it is frequently difficult to light the vapor passing from the groups of openings providing such a flame for the generator from the other openings in the burner, and it is a purpose of my invention to provide means for accomplishing this.

The ignition of the gas or vapor passing from one group of openings in the burner from the gas or vapor passing from another group that has been previously ignited, is preferably accomplished by providing a slot in the burner extending from one set of openings to an adjoining set of openings so that the vapor passing out of the slot will be ignited, thus transferring the flame from one group to an adjoining group. A similar slot is provided for transferring the flame from the burner openings in the top of the burner to the burner openings in the side of the burner which are utilized for heating the generator.

Other objects and advantages of the invention will appear as the description of the accompanying drawings proceeds. However, I desire to have it distinctly understood that I do not intend to limit myself to the exact details shown or described, but that I intend to include as part of my in-

vention all such obvious changes and modifications of parts as would occur to a person skilled in this art and as would fall within the scope of the claim.

In the drawings:

Fig. 1 is a perspective view, partly broken away, of my improved oil stove.

Fig. 2 is a section taken on the line 2—2 of Fig. 1.

Fig. 3 is a horizontal sectional view through the burner and adjoining parts of the device.

Fig. 4 is a section taken on the line 4—4 of Fig. 3 and

Fig. 5 is a section taken on the line 5—5 of Fig. 3.

Referring in detail to the drawings:

My improved stove comprises a casing 10 which is provided with suitable vent openings such as the louvers 11 therein and which is provided with upwardly extending side portions 12 and a back wall portion 13. A burner 14 is suitably supported by means of the casing 10 in any desired manner, being provided preferably with the flanges 15 for supporting the same on the casing. Said burner preferably comprises a hollow body portion that has a closed rear wall 16, closed end walls 17 and a closed inclined bottom wall 18, the bottom wall being inclined gradually from one end wall 17 to the other end wall 17 and inclining transversely as shown at 19 toward the wall portion 20 which is curved and which merges into the straight wall portion 21 spaced from a partition 22 that extends from the bottom wall 18 to the top wall 23, the extreme end portion of the partition 22 being curved as indicated at 24. A vapor chamber 25 and an air mixing chamber 26 are thus formed on the opposite sides of the partition 23. The top wall portion 23 of the burner between the wall 16, the partition 22 and a wall 27, is provided with a series of circular openings 28 within which are seated the perforated disks 29 of refractory material, said disks being provided with the closely spaced openings 30 therein communicating with the chamber 25. The openings 30 provide orifices for the passage of the vapor out of the chamber 25 so that the same may be ignited and may heat the radiant elements 31 located one over each of the disks 29. The inner face of the wall portion 23 is provided with annular enlargements or ribs 32 surrounding each of

the openings 28 to provide a larger bearing surface for the refractory disks 28. The wall portion 27 is provided with similar openings 28' in which the disks 29' having the plurality of openings 30' therein are located, said disks being substantially the same in construction as the disks 29.

The body portion of the burner which is made of a casting, is preferably provided with a forwardly extending bracket member 33 which is hook like in form and which has a curved seat 34 for the tubular generator 35, the generator 35 being mounted at the opposite end thereof in an opening 36 in the transversely extending wall portion 37, said generator opening into the chamber 26. The generator is supplied with the oil or other liquid from which the combustible vapor is made, from a tank 38 which is provided with a valve 39 leading to the pipe 40 which connects with the generator 35, a valve 41 being provided where said pipe enters said generator tube. The pressure is applied to the liquid in the tank 38 in any desired manner and any customary means for this purpose may be employed. A hood 42 is provided extending from the top wall 23 toward the generator 35 to thus direct the flame from the orifices 30' toward said vaporizer. The chamber 26 is provided with a side wall portion 43 which is connected with the wall portion 37 and which is offset from the wall portion 21 to provide a relatively large air inlet opening 44. The chamber 26 is further provided adjacent the opening 44 with a bottom wall portion 45 which is offset from the bottom wall portion 46 of the chamber 26 which inclines downwardly toward the wall 37 from the transversely inclined portion 19 of the bottom wall 18 of the chamber 25, the bottom wall 46 being slightly offset adjacent the inclined bottom wall 19 as will be clear from Fig. 5. It will also be noted that the wall portion 29 extends inwardly beyond the outer edge of the opening 44 a slight distance as indicated at 47.

Due to the depression of the bottom wall 46 below the bottom wall 18, a vertical wall portion 48 is provided extending downwardly from the wall portion 22 and said wall portion 48 is preferably provided with an internally threaded opening 49 which receives the externally threaded end portion 50 of the drain pipe 51, said drain pipe 51 inclining downwardly toward a drain receptacle 52 and having a downturned end 53 entering said receptacle. The receptacle 52 is preferably a cup-like member having a cross bar or bail 54 that is suspended from the stem portion 55 of the valve 41 by means of a hook 56. It will be seen that due to the provision of the inclined bottom 18, the inclined bottom portion 19 and the inclined bottom 46, in case any liquid enters the

chamber 25 or the chamber 26, the same will not flood said chamber but will be drained off through the opening 49 into the tube 51 and thus to the receptacle 52. This is important as it prevents the filling of the chamber with liquid which would cause the stove otherwise to smoke. This is particularly important in connection with the radiant elements, as these are particularly provided to avoid any odor or smoke, as any smoking of the burner due to liquid being burnt instead of vapor would tend to deposit smoke or carbon on the radiant elements, interfering with the proper action thereof.

When the stove is put in operation the generating tube 35 is first heated by any suitable means ordinarily provided for this purpose to vaporize the oil or other liquid producing a combustible vapor situated in the generator. The vapor then passes into the generator tube into the chamber 26 where it is mixed with air passing in through the opening 44. The vapor with air mixed with the same then passes through the curved passage 57 leading into the chamber 25 and after reaching the chamber 25, passes out through the openings 30' in the disks 29 and 29'. The disks provide groups of openings, the groups being spaced from each other. To place the stove in operation it has been necessary in devices of this character to light the gas passing through each disk 29 and each disk 29' separately to insure the lighting of all of the same, as the flame would not travel from one disk to the adjoining disk under ordinary circumstances and could not be relied upon to do this. This difficulty has been increased due to the use of the radiant elements 31. I have accordingly provided means for transferring the flame from one disk 29 to the next adjoining disk 29, comprising the slots 58, said slots extending through the top wall 28 of the burner and communicating with the chamber 25 so that the combustible vapor is passing through said slots in close proximity to the flames above the disks 28, thus making it easy for the flame to travel from one disk to another, thus insuring the substantially instantaneous ignition of the entire burner at the same time. In order to make sure that the vapor passing from the disks 29' will also be ignited, a slot 59 is provided that extends between a pair of the openings 28' adjacent a pair of said disks 29', and said slot 59 is connected with a slot 60 in the top wall 23 which, in turn, is connected with one of the slots 58. Thus the flame will travel from the disks 28 along the slot 58 to the slot 60 and then to the slots 59, and in this manner under the hood 42 where the vapor passing through the openings in the disks 29' will be ignited.

What I claim and desire to secure by Letters-Patent is:—

A burner of the character described, including a vapor chamber having an inclined bottom wall, a horizontally elongated mixing chamber, having an oppositely inclined bottom wall, communicating at its shallow end with the deep end of the vapor chamber the top walls of the chambers extending in parallel planes, and a drain conduit com-

municating with the deep end of the mixing chamber, the mixing chamber having an air 10 intake port opening thereto between the points of communication of the mixing chamber with the vapor chamber and with the drain conduit.

In testimony whereof I affix my signature.
WILLIAM KENT KISE.
